(57) **CLAIM**

The ornamental design for a press tool, as shown and described.

DESCRIPTION

FIG. 1 is a front isometric view of the press tool of the present design;

FIG. 2 is a rear isometric view of the press tool of FIG. 1;

FIG. 3 is a right side view of the press tool of FIG. 1;

FIG. 4 is a left side view of the press tool of FIG. 1;

FIG. 5 is a top view of the press tool of FIG. 1;

FIG. 6 is a bottom view of the press tool of FIG. 1;

FIG. 7 is a front view of the press tool of FIG. 1, the back view being substantially a mirror image thereof;

FIG. 8 is a front isometric view of an alternative embodiment of the press tool of the present design;

FIG. 9 is a rear isometric view of the press tool of FIG. 8;

FIG. 10 is a right side view of the press tool of FIG. 8;

FIG. 11 is a left side view of the press tool of FIG. 8;

FIG. 12 is a top view of the press tool of FIG. 8;

FIG. 13 is a bottom view of the press tool of FIG. 8; and,

FIG. 14 is a front view of the press tool of FIG. 8, the back view being substantially a mirror image thereof.

The broken lines represent the portions of the press tool that form no part of the claimed design.
